[57] CLAIM

The ornamental design of an eyeglass safety frame, as shown and described.

DESCRIPTION

FIG. 1 is a front elevation view of an eyeglass safety frame showing our new design;
FIG. 2 is a top plan view thereof;
FIG. 3 is a rear elevation view thereof;
FIG. 4 is a bottom plan view thereof; and,
FIG. 5 is a right side elevation view thereof, with the left side view thereof being a mirror image of FIG. 5.

FIG. 2

FIG. 1

FIG. 3

FIG. 4

FIG. 5
